(57) **CLAIM**

We claim the ornamental design for a digital entertainment center, as shown.

DESCRIPTION

FIG. 1 is a front, left and top perspective view of a digital entertainment center showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a front, left and top perspective view thereof, with the front panel access doors shown in an open position.
